UNITED STATES PATENT OFFICE.

OTTO HÜBNER AND ARTHUR HÜBNER, OF BRESLAU, GERMANY.

HAT-SWEAT.

SPECIFICATION forming part of Letters Patent No. 433,985, dated August 12, 1890.

Application filed February 28, 1890. Serial No. 342,168. (No model.)

To all whom it may concern:

Be it known that we, OTTO HÜBNER and ARTHUR HÜBNER, of the firm of GEBRÜDER HÜBNER, manufacturers, of Breslau, in the 5 Kingdom of Prussia and German Empire, have invented a new and useful Device for the Prevention of the Sweating and Soiling with Grease of Head-Coverings of all Sorts, of which the following is a specification, reference being had therein to the accompanying drawings.

This invention relates to a device for the prevention of the sweating and soiling with grease of head-coverings of all sorts.

15 This invention has for its object to provide an improved lining for hats, caps, and other head-coverings which shall prevent perspiration from penetrating such head-covering, and which takes place of the well-known 20 leather lining.

In using ordinary hats the perspiration which is absorbed by and penetrates the leather lining is carried either directly or indirectly by means of the stitching through 25 the exterior of the hat, which causes the latter to assume an unsightly appearance. To prevent this disfigurement there is provided, according to this invention, between the lining of the hat and the material forming the hat 30 proper a metallic band, which precludes the possibility of moisture penetrating through and to the exterior of the hat.

This invention also provides a means of uniting the metallic band and the material of 35 the hat together.

In the drawings, Figure 1 is a sectional view of a hat constructed in accordance to this invention; Fig. 2, an enlarged sectional view, and Fig. 3 a perspective sectional view, of 40 the metallic lining.

A indicates the hat as a whole, B the leather lining ordinarily employed, and C the metallic lining interposed between the leather lining and the inner face of the hat-body.

45 The metallic lining C comprises two separate bands *a* and *b*, (preferably made of a non-oxidizable material,) having their ends riveted or otherwise fastened, united, as at *c c*. Band *b* is about one-half the width of the

band *a*, and is united at its upper edge to 50 band *a*, as shown in Fig. 3, the main portion of the band *b* being set away from the inner face of band *a*, so as to form a pocket or opening *d* to receive the turned-up edge *g* of the leather lining B. 55

The main body of the leather lining B extends upward within the metallic band, and covers practically the entire inner face of the latter, thereby preventing the metallic surface from coming into contact with the 60 head.

By means of holes or slots *c* in the metal band the entire lining may be fastened to the body of the hat through the agency of metallic clamps *f*, the ends of which are passed 65 through the holes and also through the body of the hat and bent down and covered by the ribbon *k*, which is commonly employed.

If it is so desired, additional lining may be placed between the leather band B and the 70 metallic band C.

In attaching a lining to a hat according to this invention the inner leather lining B is stretched with its turned-over edge between the band *a* and *b*. The metallic band is then 75 placed inside the hat, and when adjusted to its proper height the clamps *f* are passed through the metallic band and the body of the hat, and their ends spread or bent. By using only metal in lieu of thread for the 80 fastening of the inner leather lining the passage of the perspiration by capillary attraction is entirely avoided, and since the inner leather lining does not come in contact with the felt or other material composing the 85 hat-body, but is divided therefrom by a layer of metal, passage of perspiration from the interior lining to the exterior surface of the hat is prevented and disfigurement avoided.

A lining according to this invention may 90 be quickly placed in position and changed or replaced.

Instead of forming the inner lining of leather, any other suitable tissue stuff may be used.

Having thus described our invention, what we claim is—

1. In a hat-sweat, the combination of a me-

metallic band C, composed of two parts *a* and *b* and an inner lining B of leather, the bottom edge of which is clamped between the metallic parts *a* and *b*, all substantially as shown and described.

5 2. In combination with a hat, a two-part metallic band, a strip of leather, one edge of which is secured between the two parts of the metallic band, and a fastening device passing through the metal band and the body of

the hat, all substantially as shown and described.

In witness whereof we have hereunto set our hands in presence of two witnesses.

OTTO HÜBNER.
ARTHUR HÜBNER.
